UNITED STATES PATENT OFFICE.

HADWEN SWAIN, OF SAN FRANCISCO, CALIFORNIA.

GAS-ENGINE.

SPECIFICATION forming part of Letters Patent No. 519,880, dated May 15, 1894.

Application filed August 22, 1893. Serial No. 483,768. (No model.)

To all whom it may concern:

Be it known that I, HADWEN SWAIN, a citizen of the United States, residing at San Francisco, in the county of San Francisco and State of California, have invented certain new and useful Improvements in Gas-Engines; and I do hereby declare the following to be a full, clear, and exact description of the invention, such as will enable others skilled in the art to 10 which it most nearly appertains to make, use, and practice the same.

This invention relates to improvements in gas engines, and more particularly to the governors for the same, and consists in the novel 15 construction and arrangements hereinafter fully set forth.

It has for its object to cut off the supply of gas when running above the desired speed and to do this with certainty for a full swing 20 of the piston so as to permit of no half charges which are, in the present machines, wasted. Further to exert a direct and positive force upon the cut off without depending on the centrifugal force of the governing weights to 25 maintain the action of the cut off. And further to counter-balance the governor weights to cause in them simultaneous action and overcome the independent action of gravity upon each.

30 In the accompanying drawings, Figure 1 is a side elevation of a part of a gas engine, the fly wheel being cut away to show the eccentrics and levers by which the exhaust and inlet valves are operated. Fig. 2 is a front elevation of a gas engine, being cut away to show the driving shaft and its connection with eccentrics and governor. Fig. 3 is a detail view in perspective of the eccentrics and governor. Fig. 4 is a transverse section of 35 the same, showing the relative positions of the friction wheels at the free end of the lever for operating the inlet valve. Fig. 5 is a longitudinal section of the boxing of the free end of the said lever, showing the spring by 40 which the parts are returned to their normal position after each operation.

In the drawings the letter A designates the driving shaft of the engine. Upon it is rigidly mounted the cog wheel A', which is geared 45 with a pinion B'. The pinion B' is mounted rigidly on the shaft B', on the outer end of which is mounted the eccentric B. By means of this arrangement through wheel A' and

pinion B', the desired revolution is imparted to the eccentric B from shaft A. Extending 55 out from the edge of the eccentric B is the cam C. This cam C, when the eccentric is rotated, strikes against the friction wheel C', and forces back the free arm c of the bell crank lever C², and thereby raising the arm 60 c' and connecting rod C³, which is attached to the end of the lever C⁴. The lever C⁴ being fulcrumed in the center the raising of the end to which the rod C³ is attached lowers the other end, carrying the valve rod C⁵, and 65 thereby opens the valve C⁶ on the gas pipe C⁷, and allows the gas to enter the cylinder of the engine. By this construction and arrangement it will be seen for every two revolutions of the driving shaft A the eccentric 70 B is revolved, presenting the cam C, which operates upon the levers C² and C⁴, and their connections, to open the inlet valve C⁶, permitting the introduction of gas into the cylinder to give renewed impetus to the engine. 75

To govern the speed of the engine I provide means whereby the contact point on the lever C² is moved out of the path of the cam C when a pre-determined speed has been reached, and by thus cutting off the supply 80 of gas, allow the engine to come down to its normal speed. This I accomplish in the present invention by pivoting on the eccentric B weighted arms D and D', so pivoted and weighted that the free ends will be thrown 85 apart or outward by the centrifugal force incident to the revolving of the eccentric B. To give added weight to these arms they are provided with the extensions D² D², which are extended through openings provided for 90 them in the eccentric B. To these extensions I secure the ends of the tension spring D³, which draws the arms D and D' together when not overcome by the centrifugal force caused by the heightened speed of the engine. To overcome the tendency to fall of each of the arms D D' as it passes under the center I connect them by the link D⁴, which is pivotally attached to each on the reversed 95 side of its pivot, that is to say to D', between 100 the pivot and weight, and to D, beyond the pivot away from the weight. By means of this link the tendency of either to fall is overcome by having the weight of the other to lift. While this operates to effectually prevent 105 either of the arms to move independ-

ently it in no way interferes with any tendency to spread apart simultaneously as would be produced by the exertion of any centrifugal force.

- 5 Extending out from the arm D is the cam D⁵. This cam is extended outward from the side of the eccentric at about right angles to the centrifugal force of the arms D D'. Set in the path of this cam D⁵, when the arms D 10 D' are spread, is the friction wheel D⁶ on the rod D⁷. The rod D⁷ is rigidly attached to the rod D⁸, upon the outward end of which is mounted the friction wheel C'. The rod D⁸ is passed through the boxing c² at the end of 15 the lever C², and is provided with the spiral spring D⁹, by which the wheel C' is maintained in the path of the cam C. When now the engine reaches too great a speed the rapidity of the revolution of the eccentric B produces a centrifugal force in the weighted 20 arms D D', which overcomes the tension of the spring D⁸ and throws them outward, placing the cam D⁵ in the path of the wheel D⁶. This wheel, with the rods D⁷ and D⁸ and the 25 wheel C' are then forced back, carrying the wheel C' out of the path of the cam C, thereby cutting off the supply of gas and causing the engine to run by its inertia until the speed is reduced; when the centrifugal force which 30 spreads the arms D D', being overcome by the spring D⁸, the cam D⁵ is drawn out of the path of the wheel D⁶ and the spring D⁹ allowed to return the wheel C' into the path of 35 the cam C to open the valve C⁶ and admit gas to the engine. By means of this construction of governor, half charges of gas to the engine and consequent waste of same are overcome. The cam D⁵ is placed a little in advance of the cam C, whereby it operates to 40 throw the wheel C' back before the cam C reaches it. Should, however, by reason of insufficient spread of the arms D D' the wheel D⁶ slip from the cam D⁵ the spring D⁹ could only force the wheel C' against the side of 45 the cam C, the incline of the cam having passed by the time the wheel D⁶ was drawn back.

Having thus described this invention, what I claim is—

- 50 1. In a gas engine, such as described, the combination of a lever for opening the inlet valve to admit gas to the engine, a cam connected with the running gear of the engine to engage and operate the said lever, and a 55 governor having spreading arms operated by centrifugal force, and provided with a cam operating at an angle to the spread of the said arms, adapted to remove the said lever from the path of the said cam of the running gear, 60 substantially as set forth.
2. In a gas engine, such as described, the combination of a lever for operating the inlet valve to admit gas to the engine, and provided with a spring actuated extension at the 65 free end, a cam connected with the running gear of the engine to engage the spring actuated extension on the free end of the said le-

ver, and a governor having spreading arms operated by centrifugal force and provided with a cam, operating at an angle to the spread 70 of the said arms, adapted to remove the spring actuated extension of the said lever from the path of the said cam of the running gear, substantially as set forth.

3. In a gas engine, such as described, the combination of the lever C² adapted to operate the inlet valve to admit gas to the engine and provided with extensions C' and D⁶, a cam connected with the running gear of the engine to engage extension C' and operate the lever C² and a governor having spreading arms operated by centrifugal force and provided with a cam operating at an angle to the spread of the said arms and adapted to engage the extension D⁶ and force the extension 85 C' out of the path of the cam of the running gear, substantially as set forth.

4. In a gas engine, such as described, the combination of the lever C² adapted to operate the inlet valve to admit gas to the engine 90 and provided with extensions C' and D⁶, cam C connected with the running gear of the engine adapted to engage the extension C' to operate the lever C², governor arms D D' adapted to be spread by centrifugal force, and 95 a cam connected to the arms of the governor and adapted to be placed thereby in the path of the extension D⁶ to force the extension C' out of the path of the cam C, substantially as set forth.

5. In a gas engine, such as described, the combination of the lever C² adapted to operate the inlet valve to admit gas to the engine and provided with extensions C' and D⁶, a disk B connected with the running gear of the 105 engine, cam C attached to the disk B and adapted to engage extension C', governor arms D D' adapted to be spread by centrifugal force, and cam D⁵ attached to arm D and adapted to be placed in the path of extension 110 D⁶ to force the extension C' out of the path of the cam C, substantially as set forth.

6. In a gas engine, such as described, the combination of the lever C² adapted to operate the inlet valve to admit gas to the engine, 115 the extensions C' and D⁶ attached to the free end of lever C², the eccentric B connected with the running gear of the engine, cam C attached to the eccentric and adapted to engage extension C', governor arms D D' pivotally connected to eccentric B and adapted to be spread by centrifugal force, link D⁴ attached to arms D D' to compel them to act in unison, cam D⁵ attached to arm D, adapted to be placed in the path of the extension D⁶ to force the extension C' out of the path of cam C, and spring 120 D⁹ adapted to return the extensions C' and D⁶ to their normal position, substantially as described.
